UNITED STATES PATENT OFFICE.

JACOB SCHICK, OF ORANGE, NEW JERSEY, ASSIGNOR TO MILLER REESE HUTCHISON,
OF WEST ORANGE, NEW JERSEY.

DESIGN FOR A PENCIL KNIFE.

Application filed October 10, 1923. Serial No. 7,442. Term of patent 14 years.

To all whom it may concern:

Be it known that I, JACOB SCHICK, a citizen of the United States, residing at Orange, county of Essex, and State of New Jersey, have invented a new, original, and ornamental Design for Pencil Knives, of which the following is a specification, reference being had to the accompanying drawing, forming part thereof.

I claim:

The ornamental design for a pencil knife, as shown.

JACOB SCHICK.
